UNITED STATES PATENT OFFICE.

JAMES E. WORTMAN, OF RIEDEL, MONTANA.

FILTERER FOR LAMPS.

Application filed November 22, 1927. Serial No. 235,085.

My present invention has reference to a vapor lamp of the gasoline or kerosene type, and my object is the provision of a lamp of this type with a filtering medium that is associated directly with the vapor tube.

A further object is the provision in a device for this purpose, of a vapor tube which is removably and adjustably secured in the fount of a lamp and which has its inner or lower portion widened to provide a closed chamber whose outer end, however, is apertured and is designed to have arranged thereagainst a disc of filtering material, the said disc being held against said face through the medium of a ring flange or cap that is provided with an inwardly directed lip for forcing the periphery of the filtering disc into tight contact with the ends of the vapor tube, whereby only filtered fuel can pass through the vapor tube and likewise whereby the filtering disc may be readily replaced should the same become clogged.

To the attainment of the foregoing the invention consists in the improvement as hereinafter described and definitely claimed.

In the drawings:

Figure 1 is a substantially central longitudinal sectional view through the fount of a vapor lamp showing a vapor tube therefor in accordance with this invention.

Figure 2 is a longitudinal sectional view through the lower portion of the vapor tube.

Figure 3 is a bottom plan view of the vapor tube.

Figure 4 is a transverse sectional view through the ring flange or cap.

The fount for the lamp is indicated by the numeral 1. The top of the fount is provided with a round opening formed with an inwardly directed flange which is threaded; and screwed in this flange there is a nut member 2. The nut has a central threaded opening therethrough through which is screwed the outer threaded end 3 of the vapor tube 4. The vapor tube 4 has its bottom or lower portion widened and enlarged to form the same with what I will term a chamber 5. The outer wall of the chamber is apertured, as at 6, and the side

of the cross sectionally round chamber 5 is threaded.

Designed to rest against the apertured face of the chamber 5 there is a disc 7 of filtering material such as chamois, or the like. The periphery of the filtering disc 7 is contacted by an inwardly directed flange 8 on the lower or outer end of a screw cap or ring flange 9. The member 9 is provided with interior threads and screwed on the outer threaded portion of the chamber 5. Fuel is let into the fount in the usual manner and this fuel is mixed with air under pressure and this air under pressure forces the fuel in vapor form through the filtering medium 7 and through the vapor tube and consequently prevents the generator from being clogged. The filtering disc 7 may be readily removed, should the pores thereof become clogged by dirt in the fuel, and to accomplish this it is merely necessary to remove the member 7 and to replace the filtering disc. The vapor tube 4 may be likewise easily removed from the fount by simply removing the nut 2 and unscrewing the said tube from the nut. While I have illustrated a satisfactory embodiment of my improved device, my features of invention are capable of extended application and I do not wish to be restricted to the precise details herein set forth.

Having described the invention, I claim:

In a device for the purpose set forth, a fount, a flanged nut screwed in the top of the fount, a vapor tube having one end screwed through the nut and the remainder thereof received in the fount, said tube having an enlarged end which is closed but whose outer face is apertured and the outer series of apertures being spaced away from the periphery of the said enlarged end, a filtering disc designed to be arranged against the apertured portion of the tool and a ring flange threadedly engaging said enlarged end and having an inwardly directed flange to contact with the periphery of the filtering disc.

In testimony whereof I affix my signature.

JAMES E. WORTMAN.
